DETACHABLE HANGER FASTENING MEANS

Alois A. Ritter, Racine, Wis., assignor to Hartmann Trunk Company, Racine, Wis., a corporation of Wisconsin

Application October 8, 1942, Serial No. 461,353

3 Claims. (Cl. 24—241)

This invention relates to improvements in detachable hanger fastening means.

In certain types of wardrobe hand luggage cases and trunks, garments and articles of wearing apparel are suspended from garment hangers, and the hangers are customarily provided with metallic elements to facilitate detachable engagement of the hangers with mounting means within the cases or trunks.

Due to the present scarcity of metal for civilian commodities, it is highly desirable to eliminate metal from such structures and it is, therefore, a primary object of the present invention to provide a wardrobe container garment hanger having simple and effective non-metallic, readily releasable, support-engaging means.

A further object of the invention is to provide a strap and buckle supporting means for a detachable garment hanger, said means being constructed practically entirely of leather, being flexible and adjustable, and being easily and quickly manipulatable.

A further object of the invention is to provide a leather, releasable, hanger fastening means which is of very simple construction, is strong and durable, is neat and attractive and unique in appearance, is inexpensive to manufacture, and is well adapted for the purposes set forth.

With the above and other objects in view, the invention consists of the improved detachable hanger fastening means, and its parts and combinations as set forth in the claims, and all equivalents thereof.

In the accompanying drawing in which the same reference characters indicate the same parts in all of the views:

Fig. 1 is a fragmentary plan view of a garment holding frame for incorporation in a luggage case or trunk having a garment hanger removably mounted thereon by means of the improved fastening means;

Fig. 2 is an enlarged sectional view taken on line 2—2 of Fig. 1 showing the hanger fastening means in its closed or engaged condition;

Fig. 3 is a similar sectional view only showing the relative position of elements of the hanger fastening means immediately prior to releasing the same;

Fig. 4 is a similar sectional view showing the fastening means elements partially disengaged;

Fig. 5 is a similar sectional view showing the fastening means elements completely disengaged with the hanger detached from its support; and

Fig. 6 is a fragmentary view, partly in section,

of a luggage case garment tray or section showing a garment hanger releasably mounted on another form of supporting element through the improved fastening means.

5 Referring now more particularly to the drawing, it will appear that a conventional garment hanger, such as is used in wardrobe hand luggage and in trunks, is designated by the numeral 10. The hanger is formed of wood. By way of illustration the hanger is shown in Figs. 1 to 4 inclusive as being associated with a garment folding frame 11 which includes a top longitudinal bar 12. All portions of the frame 11 are likewise formed of wood, and the frame is of such size or proportions as to fit within a compartment or section of a wardrobe case or trunk. One of the longitudinal bars 12 of the frame is, intermediate its ends, reduced as at 13 for the purpose of being embraced by an element of an improved hanger 14. The hanger 14 is formed of wood and includes a strap 15 having one end secured to the rear face of the central top portion of the hanger 10, the securement preferably being accomplished by a rivet 16 having a relatively elongated shank portion extended through the stock of the hanger and projecting substantially beyond the front face of the hanger. The strap 14 is adapted to be looped over onto the front upper face portion of the hanger, and that portion of the looped strap which ultimately registers with the front of the hanger adjacent the extended shank of the rivet 16 is provided with a relatively large opening 17 which is of eccentric or oval shape. Adapted for cooperation with the strap 14 is an elongated, relatively narrow flexible leather strip 18 doubled over or looped upon itself with the free ends in superimposed relation and mounted on the extended end of the shank of the rivet 16. The doubled or two-ply strip 18 is swingable upon the shank of the rivet 16, and the superimposed ends of the strip held by the rivet shank are rounded, as best shown in Fig. 1.

30 20 25 35 40 45 When the hanger fastening means is released and the hanger is detached from the bar 12 of the frame 11, or other support with which it is associated, the elongated turnable strip 18 is in a position removed 180° from the position shown in Fig. 1, and the apertured end of the strap 14 is lifted clear of the shoulder formed at the rounded ends of the strip 18, and is slid along the strip to the free end whereby the strip is withdrawn from the opening 17 in the strap 14. This condition or arrangement of the parts is illustrated

50 55

in Fig. 5, and it will be obvious that it is then possible to detach the fastening means from the bar 12 or other supporting means.

To engage the detachable hanger fastening means with a supporting bar or other element, said bar is passed between the free ends of the separated strap 14 and strip 17, and it is registered with the upper edge of the hanger. The strap 14 should also be registered with the reduced portion 13 of the bar 12, whereupon the free doubled end of the strip 17 is passed through the opening 16 in the strap 14 and the bent over end of the strap is moved downwardly along the outstanding strip 17, as best illustrated in Fig. 4. The next step is to snap the apertured end of the strap 14 over the shoulders formed at the extremities of the secured superimposed ends of the strip 17, and in this position the looped portion of the strap 14 will securely embrace the bar 12. This arrangement of the parts is illustrated in Fig. 3. Securement of the fastening means is effected by swinging the strip 17 on the rivet shank through an arc of 180° until the position of Figs. 1 and 2 is attained. The strip 17 then firmly compresses the front portion of the strap 14 against the hanger face, and the secured end of the strap 14 is not removable from the shank of the rivet and from the strip because of the eccentric shape of the strap opening 16 which is completely and more than covered by the superimposed rounded end portions of the strip 17.

The leather fastening means permits a limited amount of flexibility and desirable play or freedom as between the suspended hanger and the frame 11. The hanger is mounted on the frame bar very securely, but the fastening means may be quickly detached and the hanger released through a reversal of the operations described. It should be noted that when the hanger is detached from a frame or other supporting means and it is desired to use the same for hanging a garment in a closet or elsewhere, the strap 14 may be secured in looped condition with the strap 17 turned to an upwardly or outwardly extended position wherein the looped condition of the strip 17 permits it to be used as a suspension means for the hanger. The improved detachable hanger fastening means is completely devoid of metal save for the rivet 15 which, if necessary, might be formed of wood, fiber, plastic, or other non-metallic material.

A slight modification of the invention is illustrated in Fig. 6 wherein the hanger 10 is shown mounted in a tray 20, or a similar section of a wardrobe case or container, having an end wall 21. On the wall 21 there may be mounted one or more outwardly offset straps 22, and the improved hanger fastening means permits detachable engagement of a hanger 10 with a strap 22 mounted as described and shown. The hanger fastening means is precisely similar to that shown and described in connection with Figs. 1 to 5 inclusive. It will be obvious that the looped

portion of the strap 14 engages the element 22 and is releasably fastened in engaging position by the swingable strip 17.

From the foregoing description it will be seen that the improved detachable hanger fastening means is of simple and novel construction and is well adapted for the purposes set forth.

What is claimed as the invention is:

1. Hanger fastening means, comprising, in combination with a garment hanger, a strap having one end portion secured to one face portion of the hanger and adapted to have its free end portion looped over onto the opposite face portion of the hanger, the free end portion of the strap having an opening therein, a stud projecting from said opposite face portion of the hanger, and a flexible tongue having one end portion turnably mounted on said stud and forming a shoulder, the free end portion of the tongue being insertable through said strap opening to position the strap inwardly of the tongue and the stud in the opening.

2. In combination with a garment hanger, detachable fastening means therefor, comprising a wide strap having one end portion secured to one face portion of the hanger and adapted to have its free and intermediate portions looped over an edge of the hanger onto the opposite face of the hanger, the free end portion of the strap having an eccentric opening therein, a stud projecting from said opposite face portion of the hanger, and a flexible, elongated, narrow tongue having one end portion turnably mounted on said stud and forming a shoulder with the outer portion of the tongue being of looped formation, said outer portion of the tongue, when the tongue is in one turned position, being slideable through said strap opening and the strap being adapted to be forced over the tongue shoulder and stud, the tongue in another turned position having its shoulder overlying stock of the strap adjacent said opening to prevent movement of said strap portion along the tongue.

3. In combination with a garment hanger, detachable fastening means therefor, comprising a strap having one end portion secured to one face portion of the hanger and adapted to have its free and intermediate portions looped over an edge of the hanger onto the opposite face of the hanger, the free end portion of the strap having an eccentric opening therein, a stud projecting from said opposite face portion of the hanger, and a flexible, elongated, narrow tongue having one end portion turnably mounted on said stud and forming a shoulder, the outer portion of the tongue, when the tongue is in one turned position, being slideable through said strap opening and the strap being adapted to be forced over the tongue shoulder and stud, the tongue in another turned position having its shoulder overlying stock of the strap adjacent said opening to prevent movement of said strap portion along the tongue.
